UNITED STATES PATENT OFFICE.

FRANK A. WILMOT, OF BRIDGEPORT, CONNECTICUT, ASSIGNOR TO THE
WILMOT & HOBBS MANUFACTURING COMPANY, OF SAME PLACE.

DESIGN FOR A BICYCLE-FRAME.

SPECIFICATION forming part of Design No. 33,145, dated August 28, 1900.

Application filed June 11, 1900. Serial No. 19,965. Term of patent 7 years.

To all whom it may concern:

Be it known that I, FRANK A. WILMOT, a citizen of the United States, residing at Bridgeport, county of Fairfield, State of Connecticut, have invented and produced a new and original Design for a Bicycle-Frame, of which the following is a specification, reference being had to the accompanying drawing, forming part thereof.

10 The drawing is an elevation of a bicycle-frame, showing my new design.

The leading or material feature of my design consists of a bicycle-frame of the shape substantially as shown in the drawing and including as a part of said frame a seat-post tube A, smallest at its upper end and largest 15 at its lower end and with a taper extending from the lower end toward the upper end

thereof, and a lower tube B, smallest at its lower end and largest at its upper end and with a taper extending from the upper end toward the lower end thereof, these two tubes being related to each other substantially as shown in the drawing.

Having described my invention, what I claim as new, and desire to secure by Letters Patent, is—

The design for a bicycle-frame, substantially as herein shown and described.

In testimony whereof I affix my signature 30 in presence of two witnesses.

FRANK A. WILMOT.
